UNITED STATES PATENT OFFICE.

LEONARD MORGAN HAINES, OF STUDLEY, ENGLAND, ASSIGNOR TO WILLIAM HALL & COMPANY LIMITED, OF STUDLEY, WARWICK, ENGLAND.

DESIGN FOR A WRAPPER FOR NEEDLES.

Application filed October 31, 1927. Serial No. 23,960. Term of patent 3½ years.

To all whom it may concern:

Be it known that I, LEONARD MORGAN HAINES, a subject of the King of Great Britain, residing at Central Works, Studley, in the county of Warwick, England, have invented a new, original, and ornamental Design for Wrappers for Needles, of which the following is a specification, reference being

had to the accompanying drawings, forming part thereof.

The figure is a perspective view of a needle wrapper showing my new design.

I claim:

The ornamental design for a wrapper for needles, as shown.

LEONARD MORGAN HAINES.
